United States Patent Office

Des. 224,933
Patented Oct. 17, 1972

224,933

TELEPHONE ACCESSORY

Robert C. Guldstrand, 8600 Oakdale,
Canoga Park, Calif. 91304

Filed May 24, 1971, Ser. No. 146,586

Term of patent 14 years

Int. Cl. D14—03

U.S. Cl. D26—14

FIG. 1

FIG. 2

FIG. 3

FIG. 4

FIG. 1 is a top plan view showing my new design of a telephone accessory having a front control panel and telephone support pad.

FIG. 2 is a side view.

FIG. 3 is a front view.

FIG. 4 is a perspective view particularly illustrating the simulated wood grain of the telephone accessory.

I claim:

The ornamental design for a telephone accessory, as shown.
